UNITED STATES PATENT OFFICE

108,151

DESIGN FOR A RAINCOAT OR SIMILAR ARTICLE

Dorothy Cairns, New York, N. Y.

Application May 7, 1937, Serial No. 69,221

Term of patent 3½ years

To all whom it may concern:

Be it known that I, Dorothy Cairns, a citizen of the United States, residing at New York, New York, have invented a new, original, and ornamental Design for Raincoat or Similar Article, of which the following is a specification, reference being had to the accompanying drawing, forming a part thereof.

Figure 1 is a front view of a raincoat or similar article in untied condition showing my new design. Fig. 2 is a rear view of the raincoat. Fig. 3 is a fragmentary front view of the raincoat in closed position.

The raincoat is of the slip-over type having tie flaps as shown.

I claim:

The ornamental design for a raincoat or similar article substantially as shown and described.

DOROTHY CAIRNS.
